UNITED STATES PATENT OFFICE

JOHN FREDERICK DREYER, JR., OF PHILADELPHIA, PENNSYLVANIA, ASSIGNOR TO
ATWATER KENT MANUFACTURING COMPANY, OF PHILADELPHIA, PENNSYLVANIA,
A CORPORATION OF PENNSYLVANIA

RADIO POWER SUPPLY APPARATUS

Application filed May 28, 1928. Serial No. 281,078.

My invention relates to radio apparatus and more particularly to radio receiving apparatus in which signal energy is amplified at radio and audio frequencies.

In accordance with my invention, in an arrangement in which grids and anodes of at least one high or radio frequency amplifier tube and one or more low or audio frequency amplifier tubes are supplied from a common source, as for example, of rectified, filtered alternating current and more particularly in which is utilized a resistor common to the input and output circuits of the tubes to bias the grids of the tubes to a desired potential, there is provided resistance and capacity in a relation preventing reaction between the tube circuits, particularly, modulation of signal energy of radio or carrier frequencies; more specifically, a suitably high resistance is included in a direct current anode circuit of each of one or more audio amplifier tubes in series with the aforesaid common grid-biasing resistor, or equivalent, and a capacity of relatively low magnitude is utilized to provide a path for currents of audio-frequency around the source of anode current, the aforesaid high resistance, and the grid-biasing resistance, if used.

My invention resides in features of arrangement hereinafter described and claimed.

For an understanding of my invention, reference is to be had to the accompanying drawing in which:

Fig. 1 is a diagrammatic view of part of a radio system and power supply for thermionic tubes utilized therein.

Fig. 2 is a diagrammatic view of a complete radio receiving apparatus and power supply.

Referring to Fig. 1, the input circuit of the tube *v* tuned, or tunable as by condenser *k*, receives energy transferred thereto or impressed thereon by radio-frequency transformer *t*. The amplified signal energy is transferred to subsequent input circuit, as of a radio-frequency amplifier tube or of a detector tube by the radio-frequency transformer *t1*. Ultimately or directly the am-

plified energy is impressed upon the input element *t2* of the tube *v1* in whose plate circuit there is produced variations of current at audio frequency, which may be impressed upon the input circuit of a succeeding audio-amplifier tube if desired by transformer *t3*, or equivalent. For simplicity of explanation, the immediately following description is confined to a single radio-frequency amplifier tube and a single tube audio amplifier tube although it will be understood that more than one stage of either or both types of amplifier may be utilized in a complete apparatus.

The terminals of the input elements or transformer secondaries remote from the grid are connected to the negative terminal of a source HV of direct current, or rectified filtered alternating current, of suitably high voltage. Between a conductor connected to the filaments or cathodes *f* of the tubes and the negative terminal of HV is connected a resistor *r2*. The positive terminal of the source HV is connected to the anodes of the tubes. The drop of potential across resistor *r2* produced by flow of the anode current of the tubes biases their grids *g* to a suitable negative value. To prevent radio-frequency coupling effects the resistor *r2* is shunted by condenser *c3* of small magnitude and of low impedance to currents of high or radio-frequency. In the system, as thus far described, variations of the anode current at audio frequency effect changes in magnitude of the current flowing through resistor *r2* and hence of the biasing potential applied to the grid of the tube *v* modulating the energy being amplified thereby to produce undesirable and disagreeable rau-
cous noises, technically known as squawks, in any sound-reproducing instrumentality associated with the output circuit of tube *v1*.

In an attempt to avoid this effect, it is common practice to shunt the resistance *r2* with a capacity of relatively large magnitude, as 4 microfarads, which is not only expensive but wholly fails to give satisfactory results.

In accordance with my invention, there is included in the direct-current anode path

of the audio-amplifier tube $c1$, an impedance $r1$, specifically a resistance, of relatively high value and in the alternating current anode path there is included a condenser $c7$ of comparatively low value, as .5 microfarads, which by-passes the audio-frequency variations around the resistance $r1$, the source of anode current HV , and the grid-biasing resistance $r2$. The current flowing through resistance $r2$ remains substantially constant notwithstanding the audio-frequency variations of the anode current of tube $v1$ and therefore the biasing potential applied to the grid of the radio-frequency amplifier tube v is not affected to produce modulation of an incoming carrier wave. To attain comparable results with the commonly utilized arrangement above referred to, a capacity of about 30 microfarads, or more, would necessarily be utilized.

Referring to Fig. 2, the part thereof within the dotted enclosure represents the sources of alternating current for heating cathodes or filaments of the thermionic tubes of the receiving apparatus and for supplying rectified, filtered alternating current to the anode or anode circuits of the tubes, and to their control electrodes or grid circuits. The alternating current is derived from conductors 1 and 2 connected to a source G , as through a plug receptacle or lamp socket 3 connecting with the transformer primary 4 inductively related to secondaries 5, 6, and 7 delivering low voltage alternating current for heating the filaments or cathodes of the vacuum tubes of the receiving set while the secondary 8 delivers current for heating the filament or cathode of the rectifier tube 9 whose anodes are connected to the terminals 40 of the secondary 10.

Alternating current energy is supplied to the filaments or cathodes f of the tubes V , $V1$ and $V3$ by secondary 7, to the heater h of the tube $V2$ by the secondary 6, and to the filament f of the tube $V4$ by the secondary 5 to render the cathode structures of the several tubes electron-emissive. A terminal of a choke coil L , is connected to conductor 11 connected to the anodes of tubes V , $V1$ and $V4$; to conductor 12 through resistance r connected to the anode of the tube $V2$, and to conductor 13 through resistance or impedance $r1$ as in Fig. 1 to the anode of tube $V3$ to supply plate circuit current to the several thermionic tubes at different suitable voltages.

Choke coil L and condensers $C10$ connected between the terminals thereof and ground comprise a filter to eliminate or reduce to substantially negligible value the ripples in the rectified current supplied by tube 9.

The anode to cathode circuit of tubes V , $V1$ and $V3$ includes a resistor $r2$ connected 65 to earth E and to substantially the mid-

point of a resistance $r3$ connected across the terminals of secondary 7.

The grid or input circuit of these tubes is completed through the resistor $r2$, preferably having small or zero inductance, and the voltage drop across the resistance due in whole or in part to the flow of anode current therethrough is as above described utilized to effect a negative biasing potential on the grid of the tubes V , $V1$ and $V3$. The anode circuit of the tube $V4$ includes a resistance $r4$ connected between the earth E and substantially the mid-point of a resistance $r5$ connected across the terminals of secondary 5. The resistance $r4$ is included in the input or grid-tube-cathode circuit of the tube $V4$ and the drop in potential across the resistance due to the passage of anode current through it is utilized to place a negative biasing potential on the grid of the tube $V4$.

The received energy is collected by the antenna A or any equivalent collecting structure, as a loop, etc. In the example illustrated, between the antenna A , earth or counter capacity E is connected the primary of a transformer T , preferably having a step-up ratio of transformation, and across whose secondary is or may be connected the tuning condenser K whose one terminal is connected through the stabilizing resistance R with the control electrode or grid g of the first radio frequency amplifier tube V whose filament or cathode f is heated as above stated by alternating current from the secondary winding 7. The grid to filament, or input circuit of the tube is completed by condensers $c3$ connected from the filament terminals to ground. A path of the radio frequency component of the anode circuit current is through the primary of a radio frequency transformer $T1$, also preferably of the step-up type, through condensers $c2$ and $c3$ to the filament or cathode f . The secondary of the transformer $T1$ is bridged by tuning condenser $K1$ a terminal of which is connected through a stabilizing resistance $R1$ with the grid g of the radio frequency amplifier tube $V1$, and others whose terminal is connected to ground to complete the input circuit of the tube through condensers $c3$.

In the anode circuit of the tube is connected the primary of radio frequency transformer $T2$, generally similar to $T1$, and whose secondary is bridged by the variable condenser $K2$ between one of whose terminals and the grid g of the detector tube $V2$ is connected the condenser $c4$ shunted by the usual leak resistance $r8$. The cathode f of the detector $V2$ is of the equi-potential type rendered electron-emissive by the heater resistance H through which passes alternating current delivered by the secondary 6, as above described. The cathode f is connected to earth or counter capacity E and between it and

the anode of the tube is connected fixed condenser c_5 having low impedance to high or radio frequency currents. In the anode circuit is included the primary of audio frequency transformer T_3 whose secondary is connected in the grid circuit of the audio frequency amplifier tube V_3 whose output or anode circuit is coupled by the audio frequency transformer T_4 with the input circuit of the audio frequency amplifier tube V_4 whose anode is connected through a condenser c_6 having low impedance to currents of audio or voice frequency, with one terminal of the magnet within a loud speaker S whose other terminal is connected to a suitable point upon a resistance r_9 bridged across the filament of the tube V_4 . The conductor 11 is connected to the anode of the tube V_4 through choke coil L_1 having high impedance to alternating or fluctuating currents as of voice or audio frequency.

As the anode current even of the aggregate of several tubes is ordinarily small, the resistor r_2 must necessarily be of fairly high magnitude to produce a suitably large direct-current potential drop properly to bias the grids of the tubes. A negative grid-biasing potential is necessary when the filaments are supplied with raw alternating current and should be of such magnitude to insure that the grid does not become positive with respect to any part of the filament during the signal cycle. While the preferred arrangement is as shown, a resistance may be connected from the positive terminal of the source of current H.V. to the cathode end of resistor r_2 to increase the current flowing therethrough. In the system described the resistor r_2 is of about 600 ohms resistance. Utilizing this magnitude of resistance the coupling effects between the circuits to which it is common are marked and include feedback, and modulation of the radio frequency currents by the low frequency variations appearing in the anode current of the audio-frequency disturbances, or squawks.

To avoid these effects resistance r_1 connected as above described and in the relation explained in Fig. 1 is of relatively high value, for example about 12,000 ohms, to offer considerable impedance to low or audio-frequencies, and between the anode-end terminal of the resistance r_1 and the filament-end terminal of the resistance r_2 is connected a condenser c_7 having, for example, a capacity of .5 microfarads. It will be understood, however, that the values of resistance and capacity used may be varied within reasonable limits. The magnitude of capacity, for example, may be decreased to a still lower value in which event the value of resistance required, however, would be larger and would reduce the plate voltage of the tube V_3 . As the necessary magnitude of re-

sistance increases rapidly as the capacity is decreased, it is impractical, due to plate voltage requirements, for example, to continue the reduction of capacity.

It further will be understood that the resistance r_1 may be reactive, i. e. to greater or less extent inductive, or may be highly inductive, as a choke coil but for practical reasons it is preferred that r_1 be substantially a plain resistor as it is much less expensive, is very compact and is more effective, when of proper value with respect to condenser c_7 , to prevent currents of very low frequencies from traversing resistance r_2 than is a large choke coil. The total condenser capacity of the power supply in the described system is approximately 3 microfarads whereas poorer reproduction is obtained by ordinarily used arrangements utilizing at least several times that value.

Furthermore, the cathodes of radio frequency and audio frequency tubes of similar or substantially characteristics may be supplied from the same secondary of a transformer whose primary 4 is connected to a source of low frequency power supply G simplifying the power supply for the receiving apparatus.

It will be understood that tubes V , V_1 and V_3 may be of the heater type, as detector tube V_2 , in which event the heater elements may be supplied from a common secondary winding 7 or from secondary 6. The equi-potential cathodes f of each tube would then be connected to ground with the resistance r_2 included in the grid to cathode circuit of each tube.

Insofar as certain aspects of my invention are concerned, it will be understood that either or both the anode and cathode structures of the tubes may be supplied from a direct current source, as for example, a power main supplying direct current at a standard commercial voltage. The anodes of the tubes may be supplied by a shunt feed circuit as is tube V_4 without departing from my invention although the series feed arrangement shown and described is preferred.

What I claim is:

1. A radio receiving system comprising at least one audio frequency amplifying tube and one radio frequency amplifying tube, a common direct-current source of anode current for said tubes, a conductive impedance common to the grid and anode circuits of audio frequency amplifying and radio frequency amplifying tubes, traversed solely by anode current to provide a negative biasing potential for the grids of said tubes, a coupling impedance in the anode circuit of one of said tubes, and means for substantially segregating the paths of the alternating current components of the anode currents of the different types of tubes comprising a conductive impedance interposed between

the positive terminal of said source and said coupling impedance, and offering substantial impedance to flow of the alternating component of the anode current of said type of tube, and a condenser of substantially lower impedance for said alternating component connected between the cathode of said one of said tubes and a terminal of said coupling impedance remote from the anode 10 of said tube.

2. A radio receiving system comprising at least one audio frequency amplifying tube and one radio frequency amplifying tube, a common direct-current source of anode 15 current for said tubes, a conductive impedance common to the grid and anode circuits of audio frequency amplifying and radio frequency amplifying tubes, traversed solely by anode current to provide a negative biasing potential for the grids of said tubes, a transformer having its primary in the anode circuit of the audio-frequency amplifying tube, and means for substantially segregating the paths of the alternating current 20 components of the anode currents of the different types of tubes comprising a conductive impedance between the positive terminal of said source and said primary, and offering substantial impedance to flow of audio-frequency currents, and a condenser of substantially lower impedance to audio-frequency currents connected between the audio-amplifier cathode and a terminal of said primary remote from the audio-amplifier anode.

3. A radio receiving system including a resistor traversed solely by the anode currents of audio-frequency amplifying and radio-frequency amplifying tubes to bias the grids of said tubes, a common source of direct current anode current, a by-pass condenser in shunt to said resistor, a transformer having its primary in the anode circuit of the audio-frequency amplifying tube and means permitting substantial reduction 40 in the capacity of said condenser without sacrifice of quality of reproduction comprising a resistance traversed only by audio-amplifier tube current disposed between the positive terminal of said source and said 45 primary, and a condenser connected between the audio-amplifier cathode and a terminal of said primary remote from the audio-amplifier anode, the impedance of said condenser being substantially less for audio-frequencies than the impedance of said resistance, and the sum of the capacities of said condensers being substantially less than the capacity of said first condenser if used alone for the same quality of reproduction.

4. A radio receiving system comprising at least one audio frequency amplifying tube and one radio frequency amplifying tube, a common direct current source of anode current for said tubes, a conductive impedance 60 traversed solely by anode current of the

tubes and included in their input circuits for negatively biasing the grids of audio and radio frequency amplifying tubes; a transformer having its primary in the anode circuit of said audio-frequency amplifying tube and means for preventing the negative grid-biasing potential of the radio-frequency amplifying tube from varying at audio-frequencies of the audio-amplifier anode current comprising a substantially high resistance included solely in the anode circuit of the audio amplifier tube between said primary and said source of current, and a condenser of substantially less impedance for audio-frequencies connected directly between the cathode of said audio-amplifier tube and the anode end of said resistance.
